MANUFACTURING COMPANY, OF PHILADELPHIA, PENNSYLVANIA, A CORPORA-
TION OF PENNSYLVANIA.

EQUALIZING-SUPPORT FOR MOLDERS' FLASKS.

1,050,293.

Specification of Letters Patent. Patented Jan. 14, 1913.

Application filed March 22, 1912. Serial No. 685,543.

To all whom it may concern:

Be it known that I, JOHN T. RAMSDEN, a citizen of the United States, residing at the city of Philadelphia, in the county of 5 Philadelphia and State of Pennsylvania, have invented a new and useful Equalizing-Support for Molders' Flasks, of which the following is a specification.

The principal object of the present invention is to provide simple and efficient means for holding or supporting the bottom board, flask and sand mold in proper relation to the pattern and pattern board after they have been rolled over into position for without 10 drawing the pattern so that the bottom board, flask and sand mold are held in fixed lateral relation to the pattern, pattern board and their guides while the pattern is drawn and thus insure as far as possible a clean un- 15 broken edge at the sand mold; to compensate in the support for irregularities in or distortions of the pattern board, flask and bottom board, such as are due to heat, moisture and rough handling and which would 20 cause the bottom board to present an uneven surface or base upon which to support the mold, thus making it difficult to keep the surface of the mold in contact with the surface of the pattern board; and to facilitate 25 and improve the operation of the wedges which support the bottom board, flask and sand mold as well as the means by which these wedges are operated.

The invention will be claimed at the end 30 hereof but will be first described in connection with the embodiment, but not the only embodiment, of it chosen for illustration in the accompanying drawings in which—

Figure 1, is a side elevation of a part of 35 a molding machine fitted with an equalizing device embodying features of the invention. Fig. 2, is an end view of the same. Fig. 3, is a top or plan view, partly in section, of an equalizing support embodying features 40 of the invention, and Fig. 4, is a view, principally in central section, of the same.

In the drawings 1, is a base or runway.

2 and 3, are opposed taper wedges movable along the base or runway. 4, is a wedge 45 shifting device connected with and carried by the opposed wedges and adapted to shift them in opposite directions and permit either wedge to operate as an abutment in shifting the other. The device 4, is shown to com-

prise a complementary piston 5, and cylinder 6, of which the piston is connected with the wedge 3, by a pin 7, and the cylinder is connected with the wedge 2, by a pin 8.

9, is a passage for the fluid as air, water or the like for actuating the piston and cylinder. 60

10, is a connection some part of which may be flexible and which is provided with a valve 11, conveniently located for the use of the operator. 65

13, is a spring having one end connected with the piston and the other end with the cylinder and tending to draw the latter into the former.

The elements 2 and 3, obtain their wedging action when fluid is let into the cylinder and overcoming the spring 13, separates the elements on the runway, which being oppositely inclined, causes them to rise and thus block or wedge up the flask as is hereinafter 70 described.

The invention is not intended to be limited to the described wedge shifting device as it is but one embodiment of mechanism, other embodiments of which are intended to 75 be included in the invention.

In connection with the machine selected merely for illustration in Figs. 1 and 2, two bases or runways 1, each having its opposed wedges and being duplicates of each other 80 are shown. In this case the opposed wedges of each runway are connected by bars 24, having a common wedge shifting mechanism 4.

The runways are mounted on rods 14, 90 guided in ways 15, in the frame *a*, of the machine.

16, is a rock shaft having three arms of which the arms 17, are connected by links 17^a with a shaft 18, spanning the runways, 95 and of which the arm 19, is operated upon by a screw 25, driven by the toothed wheels 20. The toothed wheels 20, are driven from the hand wheel 21, by means of toothed wheels 22, and the shaft 23. The hand wheel 21, and the valve 11, may be arranged close together while the parts which they operate are at a distance and may be in a pit or otherwise not easily accessible. 100

In operation the flask *b*, with its bottom board *b*¹, and pattern board *b*², are rolled over on the arms *c* counterbalanced by the spring connection *d*. The arms *c*, rest on

stops *e*. The runways are properly positioned by the hand wheel 21, and the mechanism which it operates. The wedges are then shifted, for example, by means of the 5 valve 11, and its connections. The wedge which first contacts with the bottom board *b*¹, operates as an abutment for the other wedge or perhaps more accurately for the force which is operating between the wedges, 10 in the present instance, the piston and cylinder. In this way irregularities, if any, in the mold board *b*¹, are compensated for and the mold is evenly and firmly supported, so that when the head *f*, rises the arms *c*, draw 15 the pattern properly from the sand mold.

What I claim is:

1. An equalizing support for bottom boards and flasks comprising the combination of a base or runway, opposed taper

wedges movable along the base or runway, 20 and a wedge shifting device connected with and carried by the opposed wedges and adapted to shift them in opposite directions and permit either wedge to operate as an abutment in shifting the other. 25

2. An equalizing support for molders' flasks comprising the combination of a base or runway, wedges movable along the base or runway, a fluid cylinder and piston for operating the wedges, and means for raising 30 and lowering the runway, substantially as described.

In testimony whereof I have hereunto signed my name.

JOHN T. RAMSDEN.
